HOSIERY SHAPING DEVICE

Andrew E. Vaughan and Andrew E. Vaughan, Jr.,
 Pottstown, Pa., assignors to The Vaughan Knit-
 ting Company, Pottstown, Pa., a corporation of
 Pennsylvania

Application February 28, 1941, Serial No. 381,034

14 Claims. (Cl. 223—76)

This invention relates to devices for shaping hosiery in preparation for packing and marketing. More particularly it has reference to a hosiery shaping and creasing device of the type disclosed in a copending patent application Serial No. 288,592 filed by us on August 5, 1939, such device being characterized by a hosiery mounting form with a flat horizontal foot portion atop a transversely flat leg portion and angular cavities or depressions in opposite sides of an ankle portion at the juncture of said foot and leg portions; by presser blocks which snugly fit into said cavities or depressions; and by a creasing means for engaging a transverse creasing groove at the front of said ankle portion.

The chief aim of the present invention is to enhance the practicability of stocking shaping devices of the type specifically referred to. This objective we attain, as hereinafter more fully disclosed, through provision of means whereby the presser blocks and the creaser are separately supported for movement into and out of operative relation to the form, and through provision of simple and reliable means determining such movements of the blocks and the creaser simultaneously.

In connection with a stocking shaping device characterized as above and heated by steam or other hot fluent medium under pressure, it is a further aim of our invention to enable use of the pressure fluid to actuate the means by which the required movements are imparted to the presser blocks and the creaser. This latter objective we realize in practice, as also more fully set forth later herein through provision of an actuating cylinder and valve means for controlling the admission and exhaust of the pressure fluid into and from such cylinder.

Other objects and attendant advantages will appear from the following description of the attached drawings, wherein Fig. 1 is a perspective view of our improved hosiery shaping and creasing device with its movable parts in operative position.

Fig. 2 is a view like Fig. 1 with the movable parts in retracted position.

Fig. 3 shows the device in front elevation.

Fig. 4 shows the device in top plan with a portion in horizontal section.

Fig. 5 shows the elevation of the left hand side of the device.

Fig. 6 is a view partly in side elevation and partly in vertical section taken as indicated by the angled arrows VI—VI in Fig. 3.

Fig. 7 is a horizontal section taken as indicated by the angled arrows VII—VII in Fig. 3.

Fig. 8 is a perspective view of one of the presser blocks of the device.

Fig. 9 is a fragmentary view partly in elevation and partly in section taken as indicated by the angled arrows IX—IX in Fig. 5 and drawn to a somewhat larger scale.

Fig. 10 is a perspective view of an infant's sock or stocking after being shaped and creased by our improved shaping device.

Fig. 11 shows the sock or stocking after the leg portion has been folded down upon the foot portion as determined by the creasing.

Fig. 12 shows the reverse side of the folded sock or stocking.

Figs. 13 and 14 are views in front elevation corresponding to Fig. 3, and showing two modified forms of our improved hosiery shaping and creasing device.

Figs. 15, 16 and 17 are views in turn like Fig. 3 showing three additional modifications.

Fig. 18 is a vertical section taken as indicated by the angled arrows XVIII—XVIII in Fig. 17; and

Fig. 19 is a view corresponding to Fig. 18 and showing still another modification.

With reference first more particularly to Figs. 1—9 of these drawings, the embodiment of our invention there shown includes an upright hosiery mounting form 1 which is of integral construction and hollow throughout, with a flat horizontally disposed foot portion 2 at the top of a transversely flat vertical leg portion 3. As shown, the heel end of the foot portion 2 extends rearward of and somewhat overhangs the leg portion as at 4, and has a relatively sharp medial peripheral edge 5. The leg portion 3 of the form 1 is likewise provided with relatively sharp edges 6 medially of its sides. The foot portion 2 is connected with the leg portion through an ankle portion whereof the front and rear surfaces 7 and 8 are flat and diverge upward relative to each other at an acute angle. In each side of the 45 ankle portion is a cavity formed by three inwardly converging flat planes 9, 10 and 11. These planes 9—11, it will be noted from Figs. 2 and 6, are defined by three straight lines which intersect in a common point. Arranged to fit snugly into the respective cavities are counter-configured presser blocks 12; and extending transversely of the inclined front face 7 of the ankle portion of the form is a straight line creasing groove 13. Insofar as described up to this point, 55 our improved shaping device is substantially

identical with that shown and described in the prior patent application hereinbefore referred to.

In accordance with our present invention, the form 1 is provided with a base portion 15 which extends beyond the opposite side edges of the leg portion 3, and which is transversely rounded to fit down over a horizontal supply pipe 16 for steam or other fluid heating medium under pressure, with the vertically divided hollow of the form in registry with ports in the top of said pipe, see Fig. 6. A compressible gasket 17 interposed between the concaved base 15 and the pipe 16, insures a fluid tight juncture when the securing screws shown at 18 are fully drawn up. Also in accordance with our present invention, the presser blocks 12 are supported near the top ends of a pair of vertical arms 19. At their lower ends, these arms 19 are bifurcated as at 20 to engage over fulcrum bosses 21 on projections 22 extending laterally in opposite directions from the form 1 directly above the base 15, to which bosses said arms are connected by transverse pivot pins 23. As shown in Fig. 3, the projections have screw shanks 25 which threadedly engage into the form 1. This construction allows adjustment of the pivot centers 23 for the arms 19, the adjustment in each instance being fixable by a jam nut 26. Extending horizontally outward from each presser block 12 is a pin stud 27 which is slideable end-wise in a guide 28 secured by screws 29 to the corresponding supporting arm 19. A helical spring 30 (Fig. 4) surrounding the pin 27 within the hollow of the guide 28 and in compression between a shoulder 31 on said pin and an annular shoulder 32 interiorly of said guide permits yielding of the block as the latter is thrust into the corresponding side recess of the form. The free movement of each presser block 12 relative to the arm 19 is limited by a collar 33 at the outer end of the pin 27, said collar being secured by a set screw 34 whereof the shank passes through a longitudinal slot 34a at the corresponding end of the guide 28 to prevent the pin from turning in said guide. For the purpose of actuating the arms 19 to move the blocks 12 into and out of operative relation relative to the form 1, we have provided mechanism including a vertical slide bar 35 to which, at the lower end, is secured a block 36. As shown, this block 36 extends into the slideway 37 of a guide 38 (Figs. 3 and 6) secured by screws 39 to a machined pad 40 at the front of the form immediately above the base 15. Through a pair of toggle links 41, the presser block carrying arms 19 are coupled with a pivot screw 42 on the slide bar 35. Fulcrumed to swing on a stud 43 projecting forwardly from the guide 38 adjacent the bottom end of the latter is an actuating crank handle 45 whereto is secured by screws 46, a sectoral plate 47 with an eccentric cam slot 48 which is engaged by a roller 49 freely revolvable about a stud projection 50 on the block 36. At the top of the slide bar 35 is a vertically adjustable creaser 51 which is adapted to engage into the transverse groove 13 in the inclined front face 7 of the ankle portion of the form 1. As shown in Figs. 1-3, the creaser 51 is fashioned from a single length of wire with provision of a crosswise portion 52 at the top to fit the creasing groove 13 of the form, and pendant shanks 53 which engage parallel vertical grooves 55 at the upper end of the slide bar 35. A headed screw 56 serves to clamp the creaser in position on the slide bar 35.

In the use of the shaping device, the actuating crank handle 45 is swung to the position shown in

Fig. 2 with attendant downward movement of the slide bar 35 by action of the cam slot 48 in the plate 47 upon the roller 49 on said bar. As a consequence, the presser blocks 12 are retracted as the arms 19 are swung outward away from the form 1 under the influence of the toggle links 41, and the creaser 51 at the same time retracted from the creasing groove 13 in the ankle portion 7 of said form. With this preparation, a sock S is slipped downwardly over the form and the actuating handle 45 swung to the position shown in Fig. 1, whereby the arms 19 are moved inward to lodge the presser blocks 12 within the cavities at the sides of the form, the creaser 51 being concurrently thrust into the creasing groove 13 as shown in Fig. 9. The sock is left on the form 1 for a short time to permit its shaping under the influence of the heat, and upon subsequent removal appears, as shown in Fig. 10, so creased as to predetermine down-folding of the foot flatly upon the leg as in Figs. 11 and 12. A coiled biasing tension spring 57 engaged at one end with a fixed anchorage 58 on the base 15 of the form 1 and at the other end with an eye 59 on the crank handle 45, maintains the latter in either of its extreme positions.

In the modification shown in Fig. 13, control of the hosiery shaping device is effected through a foot treadle 60 fulcrumed midway of its length on a stud 61 in a mounting 62 secured to the floor F. A cable 63 with its ends connected to opposite ends of the treadle 60 runs over a pair of spaced idler pulleys or sheaves 65, 66 at the front of the form base 15, and at its mid point is secured to the end of an integral arm 67 on the cam sector 41. Thus, with this arrangement, as the left hand end of the treadle 60 is depressed as shown in Fig. 13, the arms 19 are moved inward toward the form 1 as the slide bar 35 is elevated under the influence of the cam sector 41. Depression of the right hand end of the treadle 60 will obviously result in downward movement of the slide bar 35 and outward movement of the arms 19. As shown, the biasing spring 57 is in this instance connected at one end to an eye 68 on the cam sector 41 so as to function in the same manner as in the first described embodiment of our invention.

In the modification shown in Fig. 14, the cam member 47 is secured to a gear pinion 70 which meshes with a gear sector 71 free on a fulcrum stud 72 extending forwardly from the lower end of a central downward projection 73 on the base portion 15 of the form 1. Pendant from the gear sector 71 is an actuating arm 75, which, when swung in the direction of the arrow in Fig. 14, will, through the medium of said gear sector, the pinion 70 and the cam 47 cause concurrent downward movement of the slide bar 35 and outward movement of the two arms 19. In this case, the biasing spring 57 is connected at one end to an anchorage 76 on the stud 72, while its other end is connected to an eye 77 on the cam member 47 as in Fig. 13.

In the modification illustrated in Fig. 15, the slide bar 35 is provided at its lower end with a plunger 80 which is confined to up and down movement in a vertical cylinder 81 at the front of the lower end of the leg portion 3 of the form 1. Axially pendant from the plunger 80 and passing through a guide aperture in a screw plug 82 at the bottom of the cylinder 81 is a rod 83 whereto is connected at its lower end, a link 85 which may in turn be connected to a foot treadle or any other suitable actuating member

or element, not shown. A helical spring 86 surrounding the rod 83 within the cylinder 81 and in compression between the plunger 80 and the screw plug 82, tends to maintain the slide bar 35 and the arms 19 in the extreme positions in which they are shown in Fig. 15. Downward pull on the rod 83 against the resistance of the spring 86 will, on the other hand, be attended by concurrent depression of the slide bar 35 and outward movement of the pressure block carrying arms 19. It is to be noted that the force of the spring 86 may be regulated by adjusting the screw plug 82 in the cylinder 81. In this embodiment of my invention, the presser blocks 12 are rigidly connected to the arms 19.

In the modification featured in Fig. 16 a cross-wise helical tension spring 90 extends between the pivot studs 91 by which the outer ends of the links 41 are connected to the arms 19, and tends to maintain the movable parts in the positions illustrated. In this instance, the slide bar 35 is prolonged downwardly as at 92 for direct guidance in a vertical slideway 93 at the front of the leg portion 3 of the form. At its lower protruding end the slide bar 35 carries a roller 94 which lies in the path of a depressing cam 95 on the link 96 of a chain 97 confined to horizontal movement in the direction of the arrow in Fig. 16 in a fixed guide channel 98. As the cam 95 over-travels the roller 94, the thrust bar 35 will obviously be depressed, the resistance of the spring 90 overcome and the arms 19 swung outwardly away from the shaping form 1 in an obvious manner. Several units of the chain following the link 96 may be provided with hold down lugs 99 to keep the roller 94 depressed with the arms 19 retracted and thereby afford sufficient time for unloading and reloading of the form. With this arrangement, it will be seen that a series of shaping forms mounted at intervals along the pipe 16 may be operated automatically in succession and the hosiery shaping and creasing process thereby carried out in a minimum of time.

In Figs. 17 and 18, a piston 100 is mounted at the lower end of a cylindric downward prolongation 101 of the slide bar 35. As shown, the piston 100 operates in a vertical cylinder 102 at the front of the leg portion 3 of the form 1, the part 101 of the slide bar 35 passing through a screw cap 103 which closes the top of the cylinder 102. The spring shown at 105 exerts downward pressure upon the piston 100 thereby normally tending to keep the slide bar 35 depressed and the arms 19 fully retracted. Lodged in the base of the cylinder 102 is a horizontal axis three way rotary valve 106. When this valve 106 is in the position shown in Fig. 18, pressure fluid is admitted from the hollow of the form 1 by way of a lateral port 107 into the bottom of the cylinder 102 as a consequence of which the piston 102 is lifted against the pressure of the spring 105, the thrust bar 35 raised, and the arms 19 retracted relative to the form. When the valve 106 is turned clockwise through an angle of ninety degrees in Fig. 18 by means of its actuating handle 108, the pressure fluid previously admitted to the bottom of the cylinder 102 is exhausted through an outlet port shown at 109, whereby the piston 100 is released to the action of the spring 105 and the slide bar 35 and the arms 19 restored to retracted positions.

In Fig. 19, the cylinder 110 in which the piston 111 at the lower end of the slide bar 35 moves is double acting and controlled by a horizontal

axis valve 112 in the cylinder base. With the valve 112 in the position shown, pressure fluid is admitted by way of a port 113 into the top of the cylinder 110 to depress the piston 111, while the bottom of said cylinder is being exhausted by way of the port 115 then in registry with a laterally-discharging outlet port 116 by way of a by-pass 117 in said valve. When the valve 112 is turned clockwise through a right angle by means of its operating handle 118, it will be seen that pressure fluid will be admitted through the port 115 into the bottom of the cylinder 110 to elevate the piston 111 and with it the slide bar 35, while at the same time the upper end of said cylinder is exhausted by way of the port 113, the by-pass 117 and another discharge port shown at 119.

Having thus described our invention, we claim:

1. A hosiery shaping device including a hosiery mounting form with foot, leg and ankle portions and having creasing cavities at opposite sides thereof, and a creasing groove cross-wise of the front of the ankle portion; presser blocks fitting the side cavities of the form; a pair of arms swingable about pivots which are fixed in respect to the form and supporting the presser blocks with capacity for movement laterally into and out of the cavities; a creaser fitting the creasing groove at the front of the ankle portion of the form; means for supporting the creaser for movement into and out of the creasing groove; means connecting the arms aforesaid with the creaser supporting means, whereby, as the creaser is moved into its groove, the presser blocks are concurrently moved into the cavities aforesaid, and vice versa.

2. A hosiery shaping device including a mounting form with a foot portion connected, through an ankle portion, with a leg portion, said form having creasing cavities at opposite sides of the ankle portion and a creasing groove transversely of the front of said ankle portion; presser blocks conformative with said cavities; a creaser element conformative with said groove; a pair of supporting arms swingable about pivots which are fixed with respect to the form, and supporting the presser blocks for movement into and out of the cavities; a separate support for the creaser; and means for concurrently actuating said arms and said support to move said blocks and the creaser into and out of the cavities and the groove respectively.

3. A hosiery shaping device including a hosiery mounting form with a horizontal foot portion at the top connected, through an ankle portion, with a vertical leg portion, and with creasing cavities at opposite sides of said ankle portion; presser blocks fitting the side cavities of the form; a pair of upright arms pivotally connected to the form at the bottom and carrying the presser blocks for movement into and out of operative relation to the form; a slide confined to up and down movement in a fixed vertical guide; a pair of toggle links by which the arms are coupled with the slide; and actuating means for shifting the slide up and down to move the presser block carrying arms toward and away from the form.

4. A hosiery shaping device including a hosiery mounting form with a horizontal foot portion at the top connected, through an ankle portion, with a vertical leg portion, and with creasing cavities at opposite sides of said ankle portion; presser blocks fitting the side cavities of the form; a pair of upright arms pivotally con-

nected to the form at the bottom and carrying the presser blocks for movement into and out of operative relation to the form; a slide confined to up and down movement in a fixed vertical guide; a pair of toggle links by which the arms are coupled with the slide; cam means cooperative with a projection on the slide to shift the slide up and down and thereby effect movement of the presser block carrying arms toward and away from the form; and means for actuating said cam means.

5. A hosiery shaping device including a hosiery mounting form with a horizontal foot portion at the top connected, through an ankle portion, with a vertical leg portion, and with creasing cavities at opposite sides of said ankle portion; presser blocks fitting the side cavities of the form; a pair of upright arms pivotally connected to the form at the bottom and carrying the presser blocks for movement into and out of operative relation to the form; a slide confined to up and down movement in a fixed vertical guide; a pair of toggle links by which the arms are coupled with the slide; a cam member mounted for oscillation about a fixed fulcrum and having an eccentric cam slot which is engaged by a projection on the slide; and means for swinging the cam member in opposite directions to effect, through the slide, movement of the presser block carrying arms toward and away from the form.

6. A hosiery shaping device according to claim 3, wherein the form is provided with a creasing groove crosswise of the front of its ankle portion; and further including a creasing member on the slide which as said slide moves upward is thrust into the creasing groove concurrently with inward movement of the presser block carrying arms to lodge the presser blocks within the side cavities of the form.

7. A hosiery shaping device including a hosiery mounting form with an ankle portion intermediate foot and leg portions, and with creasing cavities at opposite sides of said ankle portion; presser blocks fitting the side cavities of the form; means connected to the form and individually supporting the presser blocks for movement into and out of operative relation to the form; actuating means for so moving the presser block supporting means; and means whereby the presser blocks are connected to their respective supports with ability to yield independently as they enter the side cavities of the form.

8. A hosiery shaping device according to claim 3, in which the presser blocks have outward pin projections slideable endwise in guides on the respective supporting arms; and wherein springs within the guides and influential upon the pin projections permit independent yielding of the presser blocks as the latter are placed within the side cavities of the form.

9. A hosiery shaping device including a hosiery mounting form with a horizontal foot portion at the top connected, through an ankle portion, with a vertical leg portion, and with creasing cavities at opposite sides of said ankle portion; presser blocks fitting the side cavities of the form; a pair of upright arms pivotally connected to the form at the bottom and carrying the presser blocks for movement into and out of operative relation to the form; a slide confined to up and down movement in a fixed vertical guide; a pair of toggle links by which the arms are coupled with the slide; a cam member mounted for oscillation about a fixed fulcrum

and having an eccentric cam slot which is engaged by a projection on the slide; and a medially pivoted foot treadle connected by a cable with an arm on the cam member, whereby the latter may be swung in opposite directions to effect, through the slide, movement of the presser block carrying arms toward and away from the form.

10. A hosiery shaping device including a hosiery mounting form with a horizontal foot portion at the top connected, through an ankle portion, with a vertical leg portion, and with creasing cavities at opposite sides of said ankle portion; presser blocks fitting the side cavities of the form; a pair of upright arms pivotally connected to the form at the bottom and carrying the presser blocks for movement into and out of operative relation to the form; a slide confined to up and down movement in a fixed vertical guide, a pair of toggle links by which the arms are coupled with the slide; means tending to yieldingly maintain the slide in one of its extreme positions; and a travelling cam adapted to coact with a projection on the slide to move it to the other of its extreme positions in opposition to said yielding means.

11. A hosiery shaping device including a hosiery mounting form with a horizontal foot portion at the top connected, through an ankle portion, with a vertical leg portion, and with creasing cavities at opposite sides of the ankle portion, said form being hollow for circulation through it of a fluid heating medium like steam under pressure; presser blocks fitting the side cavities of the form; means connected to the form and supporting the presser blocks for movement into and out of operative relation relative to the form; a fluid pressure cylinder with a piston therein for actuating the presser block supporting means; and valve means for controlling admission and exhaust of some of the pressure fluid used in heating the form into and from the cylinder to move the piston and thereby effect, through the slide, actuation of the presser block carrying arms in the manner aforesaid.

12. A hosiery shaping device including a hosiery mounting form with a horizontal foot portion at the top connected, through an ankle portion, with a vertical leg portion, and with creasing cavities at opposite sides of the ankle portion, said form being hollow for circulation through it of a fluid heating medium like steam under pressure; presser blocks fitting the side cavities of the form, means connected to the form and supporting the presser blocks for movement into and out of operative relation relative to the form; a fluid pressure cylinder with a piston therein for actuating the presser block supporting means; a spring in one end of the cylinder influential in moving the piston in one direction; and valve means for controlling admission and exhaust of some of the pressure fluid used in heating the form into the opposite end of the cylinder to move the piston in opposition to the spring.

13. A hosiery shaping device including a hosiery mounting form with a horizontal foot portion at the top connected, through an ankle portion, with a vertical leg portion, and with creasing cavities at opposite sides of the ankle portion, said form being hollow for circulation through it of a fluid heating medium like steam under pressure; presser blocks fitting the side cavities of the form; means connected to the form and supporting the presser blocks for movement

into and out of operative relation relative to the form; a fluid pressure cylinder with a piston therein for actuating the presser block supporting means; and valve means for controlling admission of some of the pressure fluid used in heating the form, alternately into opposite ends of the cylinder to effect movement of the presser block supporting means in the manner aforesaid.

14. A hosiery shaping device including a hosiery mounting form with a horizontal foot portion at the top connected, through an ankle portion, with a vertical leg portion, and with creasing cavities at opposite sides of the ankle portion, said form being hollow for circulation through it of a fluid heating medium like steam under pressure; presser blocks fitting the side

5 cavities of the form; a pair of upright arms pivotally connected to the form at the bottom and carrying the presser blocks for movement into and out of operative relation to the form; a slide confined to up and down movement in a fixed vertical guide; a pair of toggle links by which the arms are coupled with the slide; a fluid pressure cylinder; a piston affixed to the slide and disposed within the cylinder; and valve means 10 for controlling admission and exhaust of some of the pressure fluid used in heating the form into and from the cylinder to move the piston and thereby effect, through the slide, actuation of the presser block carrying arms in the manner aforesaid.

ANDREW E. VAUGHAN.

ANDREW E. VAUGHAN, JR.
